UNITED STATES PATENT OFFICE

AUGUST MITCHELL, OF NEW YORK, N. Y., ASSIGNOR TO THE CHASE COMPANIES,
INCORPORATED, OF WATERBURY, CONNECTICUT, A CORPORATION

PORTABLE BATTERY LAMP

Application filed June 13, 1932. Serial No. 616,811.

My invention relates to an improved portable battery lamp, the object being to produce a simple, cheap, compact, attractive and convenient lamp of the character described.

5 With these ends in view, my invention consists in a portable battery lamp having certain details of construction as will be herein-after described and pointed out in the claims.

In the accompanying drawing:

10 Fig. 1 is a view in front elevation of my improved lamp, with its bail in its locked position;

Fig. 2 is a side view thereof;

15 Fig. 3 is an enlarged view showing its two-part case as open;

Fig. 4 is a transverse sectional view on the line 4—4 of Fig. 1;

Fig. 5 is a view in longitudinal section on the line 5—5 of Fig. 1;

20 Fig. 6 is a view in longitudinal section on the line 6—6 of Fig. 1;

Fig. 7 is a detached view of the bail; and

Fig. 8 is a detail sectional view on the line 8—8 of Fig. 2, showing the locking of the

25 latch by riding the bail over it to prevent the case from accidentally opening.

In carrying out my invention as herein shown, I employ a struck-up sheet-metal case comprising complementary shells 10 and 11, oblong in form, having square ends and uniting to form a two-part case substantially oval in cross-section. The said shell 10 is formed with integral pintle-sockets 12 and 13 respectively aligned with corresponding pintle-

30 sockets 14 and 15 formed upon the shell 11 aforesaid. These pintle-sockets receive the inwardly-turned pintle-ends 16 of a bail 17 substantially rectangular in form and adapted to embrace the case when the same is closed

35 and latched. As shown, the hinge also comprises a supplemental pintle 18 introduced into the sockets 12 and 15 before mentioned and held against displacement therein by the pintle-ends 16.

40 Opposite the pintle-sockets described, the shells 10 and 11 are provided upon their free edges with complementary rolled locking-ears 19, one of which forms a pivotal point for a latch 20 centrally cut away as at 21 to

45 pass over and engage with the complemen-

tary ear 19 when the latch is snapped over it to draw the two shells together. The projecting outer portions of the rolled ears are at such time exposed and form between them a seat for a locking-offset 22 formed midway 55 the length of the outer reach of the bail, whereby the same is held in its closed position, preventing the latch 20 from flying open or being moved until the bail is swung out of place.

50 The case-shell 11 is outwardly struck up and cut away to form a projecting rectangular flanged bezel 23 surrounding a sight-opening 24 normally closed by an oblong crystal 25 which rests upon the inner face of the 60 flange of the bezel, as shown in Fig. 4.

55 Within such a two-part case as described, I locate a reflector-battery-and-lamp unit, the several members whereof are constructed and assembled to be normally handled as one 70 piece. The central or key feature of this unit consists of an oblong reflector 26, the edge of which is flanged to rest upon the inner face of the crystal 25 aforesaid, the said flange snapping under locking-ribs 27 formed at opposite points, as shown in Fig. 4, on the outstanding portions of the bezel, whereby the reflector, and hence the unit, of which it is a part, is removably secured to the case-shell 11 and the crystal firmly held in place.

65 80 The said reflector 26 is formed at its ends with assembling-arms 28 bent at a right angle to its plane and respectively secured by eyelets 29 to the outer faces of complementary insulating frame-plates 30, which are se-

70 cured together in proper spaced relation by means of a bridge 31 interposed between them and secured to them respectively by the eyelets 29. Midway of its length this bridge 31

75 is widened and formed with a circular clearance-opening 33 through which passes the screw-threaded lamp-receptacle 34 which is mounted in the bottom of the oblong reflector 26.

80 85 Each of the assembling-arms 28 aforesaid is provided with a pair of fingers 35 entering notches 36 in the frame-plates 30 for preventing the rocking of the reflector upon the eyelets 29 with respect to the said plates.

85 90 The two battery-cells 37 and 38 are normally held in place on opposite sides of the 100

95 95

100

reflector 26 and against curved seats 39 in the opposite edges of the frame-plates 30 by the tension of three spring contact-plates 40, 41 and 42 secured by eyelets 43 to the outer faces of the frame-plates 30. The double contact-plate 40 is provided with two spring contact-arms 44 which form seats for the corresponding ends of the respective battery-cells 37 and 38.

10 The contact-plate 41 is provided with a spring contact-arm 45 forming a seat for the other end of the cell 37 and also with an integral inwardly-turned spring contact-arm 46 which engages with the center-button 47 of a lamp 48 which is screwed into the threaded lamp-shell 34. The said arm 46 carries a rubber buffer 49 which is engaged by the inner face of the case-shell 10, insuring the crowding of the arm 46 against the button 47 of the lamp 48, guarding against possible short-circuiting and preventing the reflector-battery-and-lamp unit from rattling in the case by pressing the flanged edge of the reflector against the edge of the inner face of the crystal 25.

25 The said contact-plate 42 is provided with a spring contact-arm 50 which forms a seat for one end of the battery-cell 38, the opposite end of which is engaged under tension with one of the spring contact-arms 44 of the double contact-plate 40. The said contact-plate 42 is also provided with a spring contact-finger 51 positioned to be engaged with and disengaged from a sliding contact-finger located within the shell 11 of the case and held in place by an operating-button 52 located upon the outside of the shell and operating through a slot 53 therein.

30 When the cells are sprung between the respective spring contact-arms of the contact-plates, the tension thus developed is sufficient to hold them in place during the handling of the reflector-battery-and-lamp unit, which comprises the lamp, its reflector, the two insulating frame-pieces, the two cells and the several contact-plates, all of these parts being assembled so as to be handled as one piece, which is a matter of much convenience in removing and cleaning the crystal and for the 35 replacement of the cells and lamp as need be.

40 My improved lamp may be either carried in the hand by means of its bail, or suspended thereby from any convenient object, or it may be supported thereby upon a table or 45 other corresponding surface by simply swinging the bail at the required angle with respect to the plane of the lamp.

I claim:

1. In a portable battery lamp, the combination with a two-part hinged shell, of a removable reflector-battery-and-lamp unit, comprising a reflector, a lamp located therein, a pair of cells located on opposite sides of the reflector, insulating frame-plates attached to the reflector, and spring contact-

5 plates carried by the said frame-plates and having spring contact-arms between which the cells are interposed.

2. In a portable battery lamp, the combination with a two-part hinged case, of a removable unit adapted to be inserted into and removed from the said case as one piece and comprising a reflector provided at its ends with assembling-arms standing at a right angle to it, frame-plates of insulating material secured to the said arms, a bridge interposed between the said frame-plates and secured thereto, a lamp located in the reflector and passing through the said bridge, contact-plates secured to the respective frame-plates and having spring-arms, and a pair of battery-cells interposed between the said arms and held in position thereby.

3. In a portable battery lamp, the combination with a two-part hinged case, of a removable unit adapted to be inserted into and removed from the case as a unit and comprising a reflector, a lamp located therein, insulating-plates secured to the reflector, contact-plates carried by the said insulating-plates and having spring contact-arms, a pair of battery-cells interposed between the said contact-arms, one of the said contact-plates having a spring contact-arm engaging with the button-end of the lamp and provided with a buffer engaged by one of the case-parts for keeping the arm in contact with the button-end of the lamp and preventing short-circuiting and assisting in holding the unit in place in the case.

4. In a portable battery lamp, the combination with a case having two complementary struck-up shells, the corresponding edges of which are provided with pintle-sockets, of a bail embracing the case when the shells are closed together and having its ends turned inwardly to enter the said sockets and form pintles for the hinge-connection of the two shells.

5. In a portable battery lamp, the combination with a case having two complementary shells having pintle-sockets upon their corresponding edges, a bail, the inwardly-turned ends of which enter the said pintle-sockets and which is adapted to embrace the case when it is closed, and a latch carried by the opposite edge of one of the shells, and means for engaging the outer reach of the bail with the said latch for locking the same in its closed position.

6. In a portable battery lamp, the combination with a case comprising two complementary shells having aligned pintle-sockets upon their corresponding edges, a bail, the ends of which are turned inwardly to form pintles entering the pintle-sockets of the said shells, locking-ears formed upon the opposite edges of the shells, a latch pivotally mounted in one of the said ears and centrally cut away to fit over the other ear, the por-

tions of the said ears projecting through the latch and receiving between them a portion of the bail after the latch is in position, whereby the bail in its closed position locks the latch in its closed position.

5 In testimony whereof, I have signed this specification.

AUGUST MITCHELL.
